BUTLER J. HASKINS, OF CHICAGO, ILLINOIS, ASSIGNOR TO JOSEPH WEIDENHOFF, INC.,
OF CHICAGO, ILLINOIS, A CORPORATION OF ILLINOIS.

SUPERCHARGER FOR MAGNETS

Application filed May 28, 1930. Serial No. 455,706.

This invention relates to an alternating current supercharger for magnetizing magnets of the type commonly used on magnetos, and the like.

Heretofore it has been customary to use direct current magnetizers, and because of the heavy current flowing special switchboards have been required to provide apparatus capable of taking care of the arc that followed on opening the high amperage circuit.

An object of the present invention is to provide a simple but effective magnetizer which will operate off the ordinary alternating current lighting circuit, and which requires no special apparatus to handle the arc generated on opening the energizing circuit.

This and other objects, as will hereinafter appear, are accomplished by this invention, which is fully described in the following specification and shown in the accompanying drawings, in which—

Figure 1 is a perspective view of the supercharger; and

Fig. 2 is a wiring diagram of the same.

The embodiment illustrated comprises a supercharger having a base 10 on which are mounted two magnets 11 and 12, which are energized by a rectified alternating current, as will later be described, and which have pole pieces 13 and 14 which are preferably placed in the same horizontal plane so as to support a magneto A, or the like, having magnets which it is desired to magnetize.

The magnet coils 11 and 12 have iron cores (not shown) which are connected through the base 10 so as to provide a continuous U-shaped magnetic path, which is open only at the top and which is completed through the magnets of the magneto A when the latter is placed thereon.

Referring now to Fig. 2. An auto-transformer 15 has a primary coil P and a secondary coil S. The ends of the primary P are connected through a suitable switch 16 and flexible leads 17 with a suitable source of alternating current 18, such as 110 volt lighting circuit. The center of the primary P is tapped with a lead 19 which connects with a central pole 20 of a double pole double throw

reversing switch 21, thereby making each half of the primary P a secondary during alternate half cycles of the energizing current. The central pole 20 connects through a knife 22 with contacts 23 and 24, depending on which way the knife 22 is thrown.

The contact 23 is connected to one end of the magnet coil 12, while the contact 24 connects through a lead 25 with the contact 26. Likewise the contact 23 connects through a lead 27 with the contact 28. A center pole 29 of this switch carries a knife 30 similar to the knife 22 which moves with the knife 22, and alternately engages the contacts 26 or 28.

The ends of the primary coil P are connected through leads 31 and 32 with the anodes or disks 33 and 34 of rectifier bulbs 35 and 36, respectively. The ends of the terminals of the filaments or cathodes 37 and 38 of these bulbs are connected by means of leads 39 and 40, and these are connected to the ends of the secondary coil S by means of leads 41 and 42, respectively. The lead 40 is also connected through a lead 43 with the central pole 29 of the reversing switch 21. The contact 26 connects through a lead 44 with one end of the magnetizing coil 11, the opposite end of this coil being connected through a lead 45 with an end of the magnetizing coil 12, the opposite end of the latter coil being connected through a lead 46 with the contact 23. The bulbs 35 and 36 and the transformer 15 are enclosed in a suitable housing 47, shown in dotted lines in Fig. 2.

The operation of this supercharger is as follows: With the switch thrown to the left, as shown in Figs. 1 and 2, and the operating switch 16 closed thereby energizing the transformer 15, an induced current from the secondary S of the transformer 15 will heat the filaments or cathodes 37 and 38 of the rectifier bulbs 35 and 36, thereby causing an electron flow from the cathodes to the anodes, first in one of these bulbs, and then in the other as the alternation of the current takes place. At the same time a flow of the current takes place from the anode 33 to the cathode 37 in the bulb 35, and the same flow alternating takes place in the bulb 36.

The current thus set up is a pulsating direct

current which flows alternately from the rectifier bulbs 35 and 36, and passes through the lead 43, the knife 30, and the lead 44, and thence through the magnet coils 10 and 12, the leads 46, 22, and 19, back to the center tap of the primary winding P.

The current that thus is caused to flow through the magnet coils 10 and 12 is of a pulsating nature, the electromotive force of 10 this energizing current tending to take substantially the form of a rectified sine wave. The inductance of the coils 11 and 12 is so great, however, that these act as shock coils causing these fluctuations to be flattened out 15 to such an extent that the current flowing is quite uniform.

It will thus be seen that with substantially a uniform direct current flowing through the magnet coils 11 and 12, the magnetic flux 20 induced in these coils will also be substantially uniform.

The operator having decided to supercharge the magnets of a magneto as A, closes the switch, thereby energizing the magnetizing 25 coils 11 and 12 in one direction. He then suspends the magneto A by a cord and brings it into the field of these coils so as to determine whether the magnetizing coils 11 and 12 are magnetized in the proper direction 30 for further magnetizing or supercharging the magnets of this magneto. If the magnetic lines of the flux are running in the same direction in both the magneto A and in the magnetizing coils 11 and 12, the magneto will be 35 drawn straight down toward the supercharger. If not, the magneto will turn as it descends so as to assume the proper charging position.

With some magnetos the operator will 40 merely turn the magneto so as to bring it to the correct position. With other forms of magnetos, however, the magneto cannot readily be reversed with respect to the pole pieces 13 and 14, and in other cases it is much more 45 desirable to do the supercharging with the magneto A set in one position rather than the reverse position.

Reversing the magnetic flux through the 50 magnetizing coils 11 and 12 is a very simple matter with this apparatus, and consists in first opening the switch 16, after which the knives 22 and 30 of the reversing switch 21 are thrown from one set of contacts across to the other, thereby reversing the direction 55 of current through the coils 11 and 12. Having done this, the operator then closes the switch 16 thereby energizing the magnetizing coils 11 and 12 in the reverse direction.

The magneto A shown is of a type having a flat base which readily adapts it to be used on the supercharger, as shown. With other types of magnetos, however, it is not such a simple matter, and adapters (not shown) 60 are applied on the pole pieces 13 and 14 to

carry the magnetic flux to the magnets to be charged.

While the transformer 15 shown is of the auto-transformer type, it will be understood 70 that a full transformer with a separate secondary winding may readily be substituted therefor.

Thus it will be seen that a very simple and effective form of magnetizing supercharger is provided. While the magnetizing current 75 flowing through the coils 11 and 12 is very heavy, the current flowing through the switch 16 is relatively small so that the switch 16 can be opened without danger to the apparatus. It will be seen, however, that the reversing switch 21 cannot be opened while current is thus flowing through the magnetizing coils, as the arc which would thus be induced would be so great as to do considerable damage both to the reversing switch and 80 to other parts of the apparatus, particularly the rectifier bulbs 35 and 36.

While I have shown and described but a few embodiments of my invention, it is to be understood that it is capable of many 90 modifications. Changes, therefore, in the construction and arrangement may be made which do not depart from the spirit and scope of the invention as disclosed in the appended 95 claims.

I claim:

1. A charger for magneto magnets comprising a transformer adapted to operate on an alternating current line, means for rectifying the current from the secondary of the 100 transformer, and a magnetizing coil supplied with current from said rectifier, said magnetizing coil being capable of charging a magneto magnet and serving as a choke for current from said rectifier so as to produce 105 a substantially even flow of current therein.

2. A charger for magneto magnets comprising a transformer adapted to operate on an alternating current line, a rectifier bulb for rectifying the current from the secondary of the transformer, and a magnetizing coil supplied with current from said rectifier, said magnetizing coil being capable of charging a magneto magnet and serving as a choke for current from said rectifier so as to produce 110 a substantially even flow of current therein. 115

3. A charger for magneto magnets comprising a transformer adapted to operate on an alternating current line, two opposed rectifier bulbs connected to the two ends of the secondary for rectifying the current from the secondary of the transformer, and two adjacent magnetizing coils supplied with current from said rectifier, said magnetizing coils serving as a choke for current from said rectifier so as to produce a substantially even 120 flow of current therein. 125

4. A charger for magneto magnets comprising a transformer adapted to operate on an alternating current line, means for recti- 130

fying the current from the secondary of the transformer, two adjacent magnetizing coils supplied with current from said rectifier, said magnetizing coils serving as a choke for current from said rectifier so as to produce a substantially even flow of current therein, and a switch in the primary circuit of the transformer for opening and closing the same.

5. A charger for magneto magnets comprising a transformer adapted to operate on an alternating current line, means for rectifying the current from the secondary of the transformer, a magnetizing coil supplied with current from said rectifier, said magnetizing coil serving as a choke for current from said rectifier so as to produce a substantially even flow of current therein, a switch in the primary circuit of the transformer for opening and closing the same, and a switch 15 for reversing the direction of flow of current through said magnetizing coil.
- 20

In testimony whereof, I have hereunto set my hand this 19th day of May, 1930.

BUTLER J. HASKINS.
